CHAUNCEY W. ABBOTT, OF AUBURN, NEW YORK, AND HENRY R. GILSON, OF BADEN, PENNSYLVANIA, ASSIGNEES TO NATIONAL METAL MOLDING COMPANY, OF PITTSBURGH, PENNSYLVANIA, A CORPORATION OF PENNSYLVANIA.

ELECTRICAL FIXTURES AND THEIR ATTACHMENT TO CONDUITS.

1,127,383.

Specification of Letters Patent. Patented Feb. 9, 1915.

Application filed May 6, 1913. Serial No. 765,383.

To all whom it may concern:

Be it known that we, CHAUNCEY W. ABBOTT, residing at Auburn, in the county of Cayuga and State of New York, and HENRY R. GILSON, residing at Baden, in the county of Beaver and State of Pennsylvania, both citizens of the United States, have invented or discovered certain new and useful Improvements in Electrical Fixtures and Their Attachment to Conduits, of which improvements the following is a specification.

Our invention relates to electrical installations wherein switches, sockets, rosettes, and similar electrical fixtures are connected to electrical conductor conduits, and has particularly to do with such fixtures when used with metal conduits.

The object of our invention is to provide a simple and an efficient means for connecting such fixtures to such conductor conduits, the arrangement being such as to eliminate the necessity of manufacturing various forms of a given fixture, differing only in their provision for attachment to one or more conductor conduits.

In the accompanying drawing, which forms part of our specification, we have illustrated two embodiments of our invention.

Figure 1 is a central sectional view of a socket and electrical conductor conduit, the socket being secured to the end of the conduit; Fig. 2 is an end view of the socket shown in Fig. 1; Fig. 3 is a top plan view of the socket and conduit shown in Fig. 1; Fig. 4 is a view similar to Fig. 1, but showing a rosette secured to an intermediate portion of the conduit; and Fig. 5 is a perspective view of the connecting plate shown in several other figures, the slot-closing lug being partly bent off.

Like numerals are used to designate like parts in the several figures.

The form of conduit illustrated herein is of a general elliptical shape, and consists of a semi-elliptical body strip 1 and a similarly shaped cover strip 2 adapted to snap upon the body strip. In making installations of such conduits the body strip is usually secured in its desired position, the electrical conductors (such as 3, 4) laid therein and the cover strip then snapped upon the body strip. It will be apparent however that our

invention is also applicable to other forms of conduits than that shown herein.

A complete electrical installation embodying our invention is illustrated in Figs. 1, 2 and 3, wherein a lamp socket is shown attached to the end of the conduit 1, 2, and 3 for the sake of additional security, the fixture is also attached to the wall 5. The lamp socket comprises a block of insulation 6 adapted to fit into the conduit body strip 1, a shell 7, and suitable conducting elements 8 and 9. The socket is surrounded by a body of insulation 10, which has, extending from one side to the other thereof, a groove or slot 11 adapted to receive the conduit 1, 2. The conduit may terminate within such slot, as shown in Fig. 1, or it may extend through it as shown in Fig. 4, presently to be described. The means, which we employ for attaching said fixture to the conduit, and which we find simple and effective for this purpose, consist of a plate 12 extending beneath the conduit and clamped to the insulation block 10 on each side of the slot 11, as by means of screws 13. The plate 12 is preferably of the same configuration as the base of the block 10, and closes the open side of the slot 11, clamping the conduit 1, 2, within the slot, and accordingly the fixture to the conduit. The plate 12 may, if so desired, be secured to a wall or support by means of a screw 14 as shown in Fig. 1; although it will be readily understood that such attachment of the plate to the wall, is not necessary in installations where the electrical fixture adds a relatively small weight to the conduit, and in such installations the clamping plate in and of itself serves to attach the fixture to the conduit. The embodiment of our invention illustrated in Fig. 4 shows a porcelain rosette 10^a, secured to a plate 12^a, which is not attached to the wall 5^a. As will readily be seen, the rosette 10^a has, adjacent to the wall to which it is attached, an enlarged concavity or recess which is closed by means of the clamping or attachment plate 12^a. Such closure is of an advantage as a precaution against fire.

The usual practice in manufacturing electrical fixtures, comprising in part blocks of porcelain or other insulating material and adapted to be used in connection with conductor conduits, has been to provide a plu-

rality of fixtures of a given general type, differing only in their provision for attachment to one or more conduits. For example, when lamp sockets, such as shown in Figs. 1, 2 and 3 of the drawing, are to be used at the end of a conduit, the block of insulation is provided with a single opening to receive the conduits, the fixtures being known as a dead end socket. And when the same general type of fixture is to be applied to the side of a continuous conduit, that is, used at an intermediate point thereof, the block of insulation is provided with two openings, thus necessitating a different fixture. Such practice, it will be understood, is expensive both for the manufacturer and dealer. To eliminate the inconvenience and expense arising from such practice, we provide one type of fixture with openings in its insulation block for connection to a plurality of conduits, and provide means for closing such conduit-receiving openings as may not be used in a given installation. In the illustrative embodiments of our invention the insulation blocks are provided with two conduit receiving openings, or, more specifically, with a continuous groove. Our preferred means for closing the unused opening consists of a lug 15 formed as an integral part of the plate 12 but partly severed therefrom, so that it may be readily broken from the plate by bending it to the plane thereof. In Fig. 1 the lug 15 is shown as closing one end of the slot 11; in Fig. 5 the lug is partly bent to the plane of the plate; and in Fig. 4 the lug has been entirely broken from the plate leaving the slot open so that the fixture may be used at an intermediate point of the conduit.

40 We claim as our invention:

1. An electrical conductor fixture comprising in part a block of insulation forming a wall around a centrally disposed open-sided recess, a plurality of openings at the margin of said wall adapted to receive electrical conductor conduits, a plate secured to said block and closing an open side of said recess, and means attached to said plate and extending at an angle thereto for closing one 50 of said conduit-receiving openings.

2. An electrical conductor fixture comprising in part a block of insulation forming a wall around a centrally disposed open-sided recess, a plurality of openings at the 55 margin of said wall adapted to receive elec-

trical conductor conduits, a plate secured to said block and closing an open side of said recess, said plate being provided with an upturned lug closing one of said conduit-receiving openings.

60

3. The combination of an electrical fixture comprising in part a block of insulation forming a wall around a centrally disposed open-sided recess, a plurality of conduit receiving openings at the margin of said wall, an electrical conductor conduit extending into one of said openings, a plate secured to said block lying in the general plane of said conduit and closing an open side of said recess and of the conduit-receiving openings, and means attached to said plate for closing an otherwise exposed conduit-receiving opening.

70

4. The combination of an electrical conductor conduit, an electrical fixture secured to a side of said conduit at an open end thereof, said fixture being provided with a slot extending from one side to the other thereof adapted to receive said conduit, and said conduit terminating within said slot, 80 and a single means for securing said fixture to said conduit and for closing the open end of said slot.

75

5. The combination of an electrical fixture comprising in part a block of insulation, a plurality of conduit-receiving openings in said block, an electrical conductor conduit extending into one of said openings, a plate attached to said block and clamping the conduit thereto, said plate being provided with an up-turned lug closing an otherwise exposed conduit-receiving opening.

85

6. A plate for connecting an electrical fixture to an electrical conductor conduit, such fixture having a continuous conduit-receiving slot therein, said plate being provided with an integral slot-closing lug partially severed therefrom and extending at an angle to the plane thereof, said lug adapted to be 100 broken from said plate by bending it toward the plane thereof.

In testimony whereof we have hereunto set our hands.

CHAUNCEY W. ABBOTT.
HENRY R. GILSON.
